© General Electric Company 1976. The drawings of this patent document contain material to which a claim of copyright is made. The copyright owner, assignee herein, has no objection to the duplication of the patent drawing but reserves all other copyright rights whatsoever. A certified copy of the certificate of copyright registration as registered by the U.S. Copyright Office is in the file of the application of this patent.

FIG. 1 is a perspective view of a doorbell escutcheon embodying my new design;

FIG. 2 is a front elevational view thereof;

FIG. 3 is a back elevational view thereof;

FIG. 4 is a side elevational view thereof;

FIG. 5 is a side elevational view of the opposite side thereof;

FIG. 6 is a top plan view thereof; and

FIG. 7 is a bottom plan view thereof.

I claim:

The ornamental design for a doorbell escutcheon, as shown and described.
